UNITED STATES PATENT OFFICE.

GEORGE MOORE, OF BOSTON, MASSACHUSETTS.

SASH FOR WINDOWS.

SPECIFICATION forming part of Letters Patent No. 587,846, dated August 10, 1897.

Application filed December 16, 1896. Serial No. 615,850. (No model.)

To all whom it may concern:

Be it known that I, GEORGE MOORE, a citizen of the United States, residing at Boston, in the county of Suffolk and State of Massachusetts, 5 have invented certain new and useful Improvements in Sashes for Windows, of which the following is a specification, reference being had therein to the accompanying drawings.

My invention has for its object to provide 10 an improved sash which shall be more particularly fitted for use in car-windows, although capable of more general use.

My invention is fully set forth in the following description, and the novel features 15 thereof are pointed out and clearly defined in the claim at the end of this specification. In the said description reference is made to the accompanying drawings, in which—

Figure 1 is an elevation of a window-sash 20 embodying my invention. Fig. 2 is a section on line 2 2 of Fig. 1. Fig. 3 is a detail of one corner of the sash, showing the construction more clearly. Fig. 4 is a view in vertical section on the line 4 4 of Fig. 1.

25 It is desirable that sashes for car-windows should combine great strength with comparative lightness, while at the same time presenting a construction which will permit of the ready removal of a broken pane of glass and 30 the insertion of another pane. By the employment of my invention a sash meeting these requirements is produced.

Having reference to the drawings, 1 is the 35 glass of the window. 2 is the bottom rail, 3 is the top rail, and 4 4 the stiles, of the sash. The top and bottom rails are formed, preferably, from wood, the edge which receives the glass in one or both of the said rails being rabbed or cut away at the inner side to permit 40 of the glass being placed in position in the said rails. When one only of the said rails is rabbed, the other will be grooved or channeled to receive the edge of the glass. After the glass has been placed in position 45 a beading 5, of wood or other suitable material, is placed next the glass on the rabbed edge of the rail and secured in place by nails 6 or other suitable securing means. The stiles each comprise an exterior piece 7, 50 preferably of metal, to give rigidity, strength, and durability to the sash, and which exterior piece 7 is of the L or angle shape in cross-

section that is shown in Fig. 2. These metal pieces form the exterior surface of the sash, as also the lateral edge portions thereof. Inside each of the said metal portions I place an L-shaped or rabbed strip 8, preferably of wood, against the thinned or rabbed edge 9 of which the edge of the plate of glass abuts. A packing 19, of rubber or the like, is employed between the glass and the stile. The thicker portion of the said strip 9 is of a thickness equal to the projecting portion of the metal part 7 of the stile, so that when the said strip is placed inside the said metal portion 55 7 the surface of the thicker portion of the said strip 9 will be substantially flush with the edge of the said projecting portion of the said metal part 7, as will be clear from Fig. 2. The said strip 8 is secured to the metal portion 7 60 by screws 10 or other suitable securing means. A retaining-strip 11 is placed in the rabbet in the said strip 8, said strip 11 being of a thickness equal to the depth of the said rabbet. It projects over the edge of the glass, 65 so that the latter is firmly held, and the strip 11 is secured to the strip 8 and metallic portion 7 by means, preferably, of screws 12, which may be unscrewed from the inside of the car when it is desired to remove the retaining-strips 11 in order to take out a broken pane and replace it by a new one. The ends 70 of the metallic portions 7 project across the ends of the top and bottom rails, the latter being grooved or cut away to receive the ends 75 of said metallic portions 7. The said top and bottom rails are united to the ends of the said metallic portions of the stiles by means of screws or similar securing devices.

By the construction above set forth a very 80 strong, durable, and relatively light sash is obtained which may be employed with advantage where, as in the case of windows which are curved vertically, there is considerable wear on the stiles in opening and closing the windows. The said construction affords ready means of removing a broken pane 85 and inserting in place thereof a new pane.

I claim as my invention—

The improved sash comprising the top and 90 bottom rails, one or both thereof being rabbed and having the removable securing-strip provided with means to retain it in place, and the stiles consisting each of the L-shaped 95

metal exterior piece, the rabbeted strip 8 against which the edge of the pane of glass abuts, and the removable retaining-strip located in the rabbet of the said rabbeted strip, 5 overlying the said pane, and provided with means to secure it in place, substantially as described.

In testimony whereof I affix my signature in presence of two witnesses.

GEORGE MOORE.
